PUSH TOY

Ralph W. Crawford, East Aurora, N. Y., assignor to
Fisher-Price Toys, Inc., East Aurora, N. Y.

Application November 12, 1957, Serial No. 48,416

Term of patent 14 years

(Cl. D34—15)

FIG. 1

FIG. 2

Fig. 1 is a top front perspective view of a push toy showing my new design; and

Fig. 2 is a fragmentary sectional view taken along line II-II of Fig. 1.

The dominant features of my new design are shown in solid lines in the drawing. A portion of the drawing figures is diagonally lined and cross-hatched to indicate a transparent material.

I claim:

The ornamental design for a push toy, substantially as shown and described.
